FASTENER

Emil Kern, Long Island City, N. Y., assignor to
 Acco Products, Inc., a corporation of New
 York

Application October 22, 1936, Serial No. 106,940

12 Claims. (Cl. 129—25)

The invention relates to improvements in paper fasteners and more particularly to that type of fastener which is adapted to be attached to a file folder or backing sheet and which includes spaced 5 apart readily detachable prongs adapted to be extended through similarly spaced openings in relatively thin or thick sheaves of paper, and a compressor adapted to engage the prongs, when the latter are bent thereover, to secure a sheaf 10 in said file folder.

Such file folders have heretofore been provided with a base element having integral or detachable prongs extending from each end which element either was permanently attached to the folder or 15 detachably secured thereto by suitable base engaging means carried on the folder. However, due to the demand for fasteners having projecting prongs positioned in various spaced apart positions and for bases having prongs of various 20 lengths to meet the requirements of files of different thicknesses, it has been necessary to manufacture and stock large quantities of fasteners of various dimensions. Other fasteners have been produced wherein the prongs are adjustably 25 attached to an extremely long base or body member for adapting the fastener to files having prong apertures spaced apart at different predetermined distances. This latter type of base is extremely objectionable because of the excessive length of 30 the base or body element when the prongs are at their innermost position of adjustment.

It is, therefore, an object of this invention to provide a paper fastener having separate detachable prongs associated with novel mounting elements for readily securing said prongs at any predetermined spaced apart relation on the file 35 folder.

Another object is to provide novel co-acting means on the prongs and on the mounting elements to insure retention of said prongs in place.

Another object is to provide novel means for retaining detachable prongs on a file folder which readily adapts the prongs for adjustment to increase or decrease the effective length thereof, 45 thereby adapting the file folder for retaining a thin or an extremely thick sheaf of papers.

Another object is to provide a fastener of the character described which does not materially increase the thickness of the file.

Another object is to provide a novel variable capacity fastener for file folders which is inexpensive to manufacture, simple to assemble, easy to adjust and positive in operation.

The foregoing and such other objects of the invention as will appear hereinafter as the de-

scription proceeds will be more readily understood from a perusal of the following specification, reference being had to the accompanying drawing, in which:

Fig. 1 is a plan view of a portion of a file folder showing the prongs in the position assumed prior to bending them substantially vertical for use.

Fig. 2 is a plan view of a portion of a file folder having detachable prongs attached thereto, showing modifications in structure and mounting.

Fig. 3 is a plan view similar to that illustrated in Fig. 2, showing another modification.

Fig. 4 is a transverse sectional view taken substantially on line 4—4 of Fig. 3, showing the prong bent.

Referring particularly to Fig. 1, the fastener base elements, indicated generally at 11, constituting one embodiment of the invention, are shown attached to the back sheet 12 of a file folder. Ordinarily the various sheets of paper to be bound in the file folder are provided with spaced apart openings to receive similarly spaced apart bendable prongs 16 which may be bent down over the top of the papers and secured in bent position in any suitable manner.

The attached end portions of the prongs 16 are held to the back sheet, as shown, by suitable mounting elements 21 each of which preferably consists of a substantially rectangular sheet of stiff material formed with an intermediate tapered rib or bridge-like portion 22 and having, at each end of each of its marginal shoe portions 23, a tang 24 which is adapted to be impaled through the back sheet 12 and clinched. The intermediate elevated bridge-like portion 22 reinforces the mounting element and provides an open ended tapered channel 25 in the bottom face of said element to receive one prong 16.

In assembly, the mounting elements 21 are securely attached to the back sheet and the prongs 16 are then inserted one through each channel 25. Sliding movement of the prongs along the respective channels 25 is limited in one direction preferably by slitting and flaring the attached end of each prong, as at 26. The projecting end portion of each prong then is bent substantially at right angles to the back sheet 12 against the opposed end of the respective mounting elements whereby said prongs are firmly held against sliding displacement. Inasmuch as the channels 25 are tapered substantially the same amount as the taper of the prong ends, the side walls 27 of said channels prevent lateral shifting or twisting of the prongs thus maintaining them substantially parallel to each other for easy inser-

tion through the openings in the sheaf of papers.

It is obvious that the mounting elements may be suitably positioned on the back sheet to position the bent up substantially vertical portions of the prongs 16 in any desired spaced relation for insertion through predetermined spaced openings in the sheaf and that it is, therefore, unnecessary to manufacture or stock a complete line of base members of various lengths, it being necessary 10 only to carry a stock of compressors of various sizes.

The modified forms shown in Figs. 2 and 3 are substantially like that form previously described and each is adapted for use for binding the papers in a sheaf, and like numbers, therefore, are used to designate similar parts.

The prongs 16^c shown in Fig. 2 preferably are each provided with an upwardly extending projection 32 which, when the prongs are in secured position, are adapted to engage in openings 33 in the intermediate bridge-like portions 22^c of the respective mounting elements 21^c. To facilitate insertion of the prongs 16^c the intermediate bridge-like portions preferably are slit, as at 34, 20 to permit flexing upwardly of the adjacent portions of said elements during the travel of the projections 32 into the respective openings 33.

In Figs. 3 and 4 each mounting element 21^d has a depressed detent projection 35 preferably located substantially centrally on the intermediate bridge-like portion 22^d for engagement in any one of a plurality of holes 36 in the respective prong 16^d. Accordingly, this type of prong may be adjusted in length to adapt it to files of various 30 thicknesses and said prong is securely held against longitudinal displacement or lateral shifting.

Although several embodiments of the invention have been described in detail it is to be understood that the description thereof is illustrative rather than restrictive as many details may be modified or changed without departing from the spirit of the invention or the scope of the appended claims.

45 I claim:

1. In a folder, a back sheet, a mounting element secured to said sheet, a channel in the bottom face of said element, a separable prong inserted through said channel and adapted to be 50 bent over against one end of said element, and means on said prong and in said channel coacting to retain said prong in position.

2. A mounting element adapted to detachably 55 secure a paper fastener prong to a file folder comprising, a substantially rectangular sheet of material having a channel formed in its bottom face to receive said prong, said channel being substantially of the same width as said prong to prevent lateral shifting of the latter, securing 60 tangs on said element, and means in said channel adapted to co-operate with said prong to prevent inadvertent removal of said prong.

3. In a folder, a back sheet, a mounting element secured to said sheet, a bridge-like portion 65 in said element, a separable prong inserted beneath said bridge-like portion, said bridge-like portion having an opening, and a projection on one end of said prong engaged in said opening to prevent inadvertent removal of the prong.

4. In a folder, a back sheet, a mounting element secured to said sheet, a bridge-like portion in said element, a separable prong inserted beneath said bridge-like portion, said bridge-like portion having a slotted opening, and a projection on one end of said prong engaged in said opening to prevent inadvertent removal of the prong. 5

5. A mounting element for a paper fastener comprising, a substantially rectangular body, a bridge-like portion formed in said body having an opening, and securing tangs on said body. 10

6. In a folder, a back sheet, a mounting element secured to said sheet, a bridge-like portion in said element, a separable prong inserted beneath said bridge-like portion, and means in said bridge-like portion and on said prong engaged to prevent inadvertent removal of said prong. 15

7. A mounting element adapted to detachably secure a paper fastener prong to a file folder comprising, a substantially rectangular sheet of material having an intermediate bridge-like portion to embrace a prong insertable therebeneath, 20 securing tangs on said element, and means formed in said bridge-like portion adapted to coact with means on the prong to prevent inadvertent removal of said prong.

8. A mounting element adapted to detachably 30 secure a paper fastener prong to a file folder comprising, a substantially rectangular sheet of material having an intermediate bridge-like portion to embrace a prong insertable therebeneath, securing tangs on said element, and means 35 formed in said bridge-like portion adapted to frictionally engage means on the prong to prevent inadvertent removal of said prong.

9. In a folder, a back sheet, a mounting element secured to said sheet, a bridge-like portion 40 in said element, a separable prong inserted beneath said bridge-like portion, said prong having spaced openings therein, and means in said bridge-like portion to co-operate with said openings to retain the prong in any one of a plurality of positions. 45

10. A mounting element for a paper fastener comprising, a substantially rectangular body, a bridge-like portion formed in said body having substantially vertical side walls, said side 50 walls being inclined longitudinally toward each other, and means to secure said element to a backing sheet.

11. In a folder, a back sheet, a mounting element secured to said sheet, a bridge-like portion 55 in said element having substantially vertical side walls, said walls being inclined longitudinally towards each other to provide a tapered channel on the under side of said bridge-like portion, a separable prong inserted in said channel, and a flared end on said prong to co-act with the tapered channel to limit movement of said prong in one direction. 60

12. In a folder, a back sheet, a channelled mounting element on said back sheet, said channel being tapered, and a separable prong inserted in said channel, said prong having a flared end to co-act with said tapered channel. 65

EMIL KERN.
